DESIGN FOR A DRESS

Ida Lampel, New York, N. Y.

Application January 7, 1939, Serial No. 82,209

Term of patent 3½ years

To all whom it may concern:

Be it known that I, Ida Lampel, a citizen of the United States, residing at 525 Seventh Avenue, city of New York, in the county of New York and State of New York, have invented a new, original, and ornamental Design for a Dress, of which the following is a specification, reference being had to the accompanying drawing, forming part thereof.

The characteristic feature of my design resides in the combination on the specific dress disclosed of the specific embroidered lace inserts in the shoulders and on the bottom of the skirt as shown.

I claim:

The ornamental design for a dress, substantially as shown and described.

IDA LAMPEL.
